DESIGN FOR A MERCHANTISE DISPLAY CASE

Maxfield Gluckman, Jackson Heights, N. Y.

Application July 21, 1947, Serial No. 140,429

Term of patent 14 years

(Cl. D80—11)

To all whom it may concern:

Be it known that I, Maxfield Gluckman, a citizen of the United States and a resident of Jackson Heights, in the county of Queens, State of New York, have invented a new, original, and ornamental Design for a Merchandise Display Case, of which the following is a specification, reference being had to the accompanying drawing, forming part thereof.

In the drawing the single figure is a perspective view of the merchandise display case, showing my new design.

I claim:

The ornamental design for a merchandise display case, as shown.

MAXFIELD GLUCKMAN.
